UNITED STATES PATENT OFFICE.

WILLIAM DECKER, OF COLFAX, ASSIGNOR OF THREE-FOURTHS TO JOHN H. HUGGIN, EDWARD ANNABLE, AND DAVID TRAVIS, ALL OF FAIRBURY, ILLINOIS.

VALVE.

SPECIFICATION forming part of Letters Patent No. 252,195, dated January 10, 1882.

Application filed October 11, 1880. (No model.)

To all whom it may concern:

Be it known that I, WILLIAM DECKER, of Colfax, county of McLean, State of Illinois, have invented a new and useful Improvement 5 in Valves for Controlling the Flow of Water, of which the following is a specification.

My invention relates to an improvement in valves, the object being to provide an article of this character which shall be adapted to automatically control the flow of water into a vessel, and which shall combine with simplicity and cheapness of construction durability in use.

With these ends in view my invention consists in certain details in construction and combinations of parts, as will hereinafter be described, and pointed out in the claims.

In the accompanying drawings, Figure 1 is a view in vertical section of a water-vessel provided with a valve constructed in accordance 20 with my invention, and Fig. 2 is a plan view thereof with the floating weight removed.

A represents a vessel of any desired form, and C a pipe supplying it with water from any convenient source. D is a valve-chamber, into 25 which the said pipe C discharges its contents, which flow from thence into the vessel A through an egress-port, d, formed in the upper wall of the chamber. A hinged valve directly attached to the interior wall of the said chamber is 30 adapted, as will be hereinafter described, to automatically open and close communication between it and the vessel A by covering, under certain conditions, the egress-port d.

A float, F, of any desired size, construction, 35 or material, and arranged to be floated by the water in the vessel A after it has attained a predetermined height therein, is connected to the hinged valve E, described above, by a rod, e, or any suitable equivalent therefor. It is 40 desirable that the connection between the said valve and rod be a pivotal one, in order that as the valve is opened and closed the rod which actuates it in such motion may always reciprocate in a vertical plane, while the connection 45 between the said rod and float should be vertically adjustable to permit the regulation of the height to which the water must rise in the vessel A before the float is buoyed thereby.

In the fulfillment of this last-recited principle of construction the float may be centrally 50 pierced with an interiorly screw-threaded aperture and the upper end of the rod screw-threaded; or any other equivalent method of adjustment may be resorted to.

G is a bar or guide interposed between the float and the top of the valve-chamber D, and adapted to fulfill the twofold function of securing to the guide a vertical reciprocation and of supporting the float when not buoyed by water in the vessel A, and bearing a weight 60 which would otherwise fall on the valve E. In order that the bar may fulfill this function, it should be located a little below the water-line at which the float is buoyed. In the fulfillment of its first-named function it is provided 65 with a perforation exactly registering with the egress-port d, and arranged to receive the guide-rod e.

It is obvious that many devices for fulfilling the designs of the guide G may be adapted in 70 lieu thereof. For instance, a frame secured to the side of the valve-chamber may be arranged to extend over the top thereof and guide the rod e and support the unbuoyed float. It is particularly necessary that a guide of some 75 character be employed, as otherwise the float, in changing its position on the water, which it is left free to do, will tend to wrench the hinge-bearing of the valve.

Having described my invention, I will briefly 80 set forth its mode of operation. Supposing the vessel E to be empty, if water be admitted to the valve-chamber D through the pipe C, it will flow from said chamber into the vessel A through the egress-port d. When water nearly 85 fills the vessel A the float F will be buoyed thereby, and slowly rising close the port d by means of valve E, which it operates by means of rod e. The valve E will remain closed until the subsidence of the water lowers the 90 float, which will, in falling, open the valve and again allow the water to pour into the outer vessel.

It is not necessary that the valve mechanism should be located in the receptacle from 95 which the water is withdrawn; but it may as

well be located without and connected with it by suitably-arranged water-conduits.

When the water flows into the valve-chamber under much head it will tend to close the valve in antagonism to the weight of the float. 5 In such case the weight of the float should be regulated in proportion to the force of the water-pressure.

Among the advantages claimed for this form 10 of valve over others may be mentioned that of cheapness, as it does not require the nice adjustment necessary to the operation of circular and hemispherical valves; the advantages of durability and simplicity, the parts being few 15 and simple and the adjustment such that the wear on the parts is very slight, and the important advantage of surety of action, the arrangement of the parts precluding a displacement of them.

20 I would have it understood that I do not limit myself to the exact construction of parts shown and described, but hold myself at lib-

erty to make such slight changes and alterations as fairly fall within the spirit and scope of my invention.

Having fully described my invention, what I claim as new, and desire to secure by Letters Patent, is—

1. The combination, with the chamber D, having an eduction-port and a valve hinged 30 to close upwardly and cover said port, of a float and a stem secured at one end to the float and at the other end hinged to said valve, substantially as set forth.

2. A supply-pipe, C, receptacle A, chamber D, with ports *c* and *d*, and floating weight F, in combination with a hinged valve attached to the inner surface of chamber D near the egress-port *d*, and suitable connections between the valve and floating weight, as set forth.

WM. DECKER.
